UNITED STATES PATENT OFFICE

CHARLES W. HORTON, OF MIAMI, FLORIDA

DOOR OPERATING MECHANISM

Application filed January 26, 1931. Serial No. 511,402.

This invention relates to door operating mechanisms for opening and closing doors of various types and may be advantageously used for opening and closing the doors of elevators. An object of the invention is to provide electrically operated means which may be rendered active to move the door from an open to a closed position and vice versa, and to automatically interrupt operation of the mechanism at the limit of movement of the door in either direction.

Another object of the invention is the provision of automatically operated means for normally holding the door against movement until a circuit is closed through the electric drive of the door mechanism, and thus provide for the safety of persons entering or leaving the elevator.

Another object of the invention is the provision of means actuated by the elevator door operating mechanism for operating and controlling the operation of the elevator shaft doors.

Another object of the invention is the provision of means of the above character which are simple and reliable in construction and operation, may be manufactured and applied as factory equipment, or may be separately sold and fitted to various types of doors where automatic operation is desired.

With the above and other objects in view, the invention further includes the following novel features and details of construction, to be hereinafter more fully described, illustrated in the accompanying drawings and pointed out in the appended claims.

In the drawings:—

Figure 1 is a fragmentary elevation illustrating the invention, a portion of the elevator shaft door carried means being shown in section.

Figure 2 is a fragmentary top plan view.

Figures 3, 4 and 5 are sectional views taken respectively on the lines 3—3, 4—4 and 5—5 of Figure 2.

Figure 6 is a section taken substantially on the line 6—6 of Figure 1.

Figure 7 is a section taken substantially on the line 7—7 of Figure 2.

Figure 8 is a section on the line 8—8 of Figure 2.

Figure 9 is a diagram of the circuits.

Figure 10 is a fragmentary elevation partly in section illustrating the clutch for throwing out the door operating mechanism.

Referring to the drawings in detail where in like characters of reference denote corresponding parts, the reference character 10 indicates a portion of the door of an elevator or car which may be of any desired type and which is shown as of the collapsible or foldable type hung upon curved rollers 11 which operate over a track or rail 12 carried by the elevator (not shown). The reference character 13 represents a portion of one of the doors of the elevator shaft, the frame or jamb of which is indicated at 14, it being of course understood that the shaft will be provided with a door for each floor or landing.

Adapted to be mounted upon the elevator by any suitable means is a housing 15. Extending through this housing is a worm shaft 16, upon which is mounted a worm 17. This shaft operates in anti-friction bearings 18 and extends through stuffing boxes 19 so that the housing may be filled with oil for proper lubrication and silent operation of the parts.

Loosely mounted upon the shaft 16 is a sprocket 20 which is adapted to frictionally engage a collar 21 which is fast on the shaft 16. The sprocket 20 is driven by a chain 22, which may be operated by an electric motor M. This sprocket is provided with a cone face 23 for engagement by the conical end of a clutch member 24 which is splined to the shaft 16 as shown at 25. A spring 26 normally urges the clutch member 24 into frictional engagement with the cone face 23, and the tension of this spring may be regulated by means of a nut 27 mounted upon the end of the shaft 16. A frictional drive is thus provided for the shaft 16, so that in the event of accident or failure of any of the parts of the mechanism to be described, a slippage will be provided between the sprocket 20 and the shaft.

Extending from the housing 15 are upper and lower guide bars 28 and 29 respectively, the remote ends of these bars being mounted

in a housing 30 which is also adapted to be carried by the elevator. These guide bars have mounted thereon a carriage 31, which as shown in Figure 4 of the drawings, is bifurcated to engage over a guide rail 32. Extending downwardly from the carriage 31 are spaced arms 33 which are bolted or otherwise secured to the elevator door 10 as shown at 34. By this means, when the carriage is moved longitudinally of the guide rods, the elevator door 10 will be likewise moved from a closed to an open position, or vice versa, depending upon the direction of movement of the carriage.

15 In order to move the carriage there is provided a sprocket chain 35. This chain passes around a sprocket 36 which is mounted upon a short shaft 37 which is in turn mounted in anti-friction bearings 38 carried by the housing 15. A collar 39 is fast upon the shaft and this collar is provided in its outer face with recesses 40, while teeth 41 which extend from a collar 41a attached to the sprocket 36 engage within these recesses, and as the collar 20 39 is fast upon the shaft 37, rotation of the latter will rotate the sprocket. The chain 35 also passes around a sprocket 42 which is mounted upon a short shaft 43 provided in the housing 30, and as this chain engages 25 teeth 44 carried by the carriage 31, rotation of the shaft 37 will move the carriage longitudinally of the guide rods. A driving connection between the shaft 16 and the shaft 37 is effected through the medium of the worm 30 35 17 and a worm wheel 45 mounted upon the shaft 37.

The collar 39 is formed upon one end of a sleeve 39a, to which is keyed the worm wheel 45, the sleeve being free to rotate upon the shaft 37. The shaft 37 is also capable of longitudinal movement within the sleeve and the collar 41a is keyed to the shaft as shown at 37a. The sleeve 39a is provided internally with spaced annular grooves *a* and *b*, as shown in Figure 5 of the drawings, and these grooves are adapted to receive a spring pressed ball *c* which is movable in a diametrically disposed recess provided in the shaft 37.

When the parts are in the position shown in Figure 5 of the drawings, the drive will be from the worm gearing, through the sleeve, the collars 39 and 41a, and the sprocket chain 35. In the event of trouble with the operating mechanism, the collar 41a may be moved axially by pulling outwardly on the same until the teeth 41 are disengaged from within the recesses 40, whereupon no rotation of the sprocket 36 will occur. In this position the ball c will be within the recess b .

the ball 3 will be within the recess 5.

60 Supported by the housing 15 is a switch S, while supported by the housing 30 is a switch S'. Each of these switches includes spaced contacts 46 which are adapted to be engaged by contacts 47 47' which are pivotally mounted as at 48. An operating arm 49 extends

65

from each of the contacts 47 47' and acts to normally hold these contacts in position to bridge the contacts 46. The contacts 46 of the switch S are electrically connected to the motor M by means of a conductor 50 which is tapped on to a conductor 51, while the contact 47 of this switch is connected by a conductor 52 with one post 53 of a switch 54. The contact 47' of the switch S is connected by a conductor 55 with another terminal 56 of the switch 54 while a conductor 57 leads from the other contact 46 to the motor through a conductor 58.

The contacts 46 of the switch S' are connected to the motor M through conductors 59 and 60, while the contacts 47 and 47' of the switch S' are connected to contacts 61 and 62 respectively by conductors 63 and 64. 80

In order to operate the switches S and S', the carriage 31 has extending therefrom oppositely disposed arms 65 and 66. The arm 49 of the switch S is arranged in the path of the arm 65, while the arm 49 of the switch S' is arranged in the path of the arm 66 so that when the carriage reaches its limit of movement in one direction, the arm 65 will open the switch S and when the carriage reaches its limit of movement in an opposite direction, the arm 66 will open the switch S'. 85 90

Rigid upon the shaft 16 is a brake wheel 67 having a grooved periphery 68 and operating within this periphery are arcuate friction elements 69 which are carried by brake shoes 70. These shoes are pivotally mounted as at 71 between the upstanding plates 72 of a switch stand 73, and extending from these shoes are arms 74 to which are pivotally mounted as at 75, the outer ends of plungers 76. These plungers extend into the opposite ends of a magnetic coil 77 which when energized, will draw the plungers inward and move the shoes relatively outward upon the pivots 71. The upper ends of the shoes carry apertured lugs 78 through which passes a rod 79, and springs 80 mounted upon this rod act to yieldingly force the friction elements 69 into engagement within the grooved periphery of the wheel 67. The coil 77 is bridged across the conductors 59 and 60, by means of conductors 81 and 82.

Current for the operation of the motor may be supplied from a suitable source, for example, the line wires 83 and 84. These line wires are connected to suitable contacts 85, while contacts 86 spaced therefrom are connected with the switch 54 by means of conductors 87 and 88. The contacts 85 and 86 are stationary and are adapted to be bridged by movable contacts 85a operated by means of a magnetic coil 86a connected in an auxiliary circuit which includes conductors 86b and 86c. The conductor 86c is connected to one of the contacts 86d of a switch W, the latter including a pivotally mounted arm 86e which carries a contact 86f. 130

to which is attached a conductor 86g. The conductors 86b and 86g may be connected in any suitable manner with a source of current.

The arm 86e also carries a contact 86h which is adapted to engage a stationary contact 86i, both of which are connected in circuit with the elevator operating motor M'.

By reference to Figure 9 it will be seen that when the switch W is positioned to close the circuit through the motor M', the circuit through the coil 86a will be open and consequently the circuit to the door motor M cannot be closed. Conversely, when the contacts 85-86 and 85a are engaged, a circuit may be completed through the motor M, while the switch W will be arranged to prevent closing a circuit through the motor M'.

As thus far described, assuming that the elevator door is closed, the coil 77 will be energized, so that the springs 80 will cause the friction elements of the brake shoes to tightly engage the brake wheel 67 and prevent operation of the parts until the coil 77 is energized. However, this coil cannot be energized until the contacts 85 and 86 are bridged. As the contacts 85 and 86 are positioned at each of the elevator landings, no current is supplied to the motor between these landings. As soon as the elevator reaches a landing, the contacts 85 and 86 are in position to be engaged by the contacts 85a, but the door cannot be opened until the switch 54 is closed and switch W operated through the usual elevator controller to open the circuit to the motor M'.

The elevator door being closed, the arm 66 of the carriage will engage the arm 49 of the switch S', so as to open this switch, the switch S being closed. By throwing the switch 54 so as to engage the contacts 53 and 56, current will flow from the switch 54 through the conductor 55, the contact 47', its contact 46, the conductor 57, the conductor 58, the motor M, the conductor 51, the conductor 50, the other contact 46, the contact 47 through the conductor 52 back to the contact 53 of the switch 54. In addition, current will flow through the coil 77 so as to energize the latter and release the shaft 16. Operation of the motor will operate the chain 35 so as to move the carriage 44 away from the switch S', and move the door 10 to an open position. As soon as the arm 65 reaches the arm 49 of the switch S, this switch will be open to interrupt flow of

current through the motor and through the coils 77, so that operation of the motor will stop and the brake shoes will be applied. When it is desired to close the door, the switch 54 is operated to engage the contacts 61 and 62, so that current will flow through the conductor 64, the contact 47 of the switch S', its contact 46, the conductor 59, the conductor 51, the motor M, the conductor 58, the conductor 60, the other contact 46, the contact 47' and back to the switch through the

conductor 63. The current will thus travel through the motor in an opposite direction so that the direction of the motor will be reversed to reverse the direction of movement of the door. As soon as the switch 54 is closed, the coil 77 will be again energized to release the wheel 67.

In order to also control the operation of the shaft doors 13, each of these doors has extending therefrom a bracket 89. Pivotedly mounted upon this bracket as at 90 is a toothed latch 91, the teeth of which are adapted to engage a keeper plate 92 carried by the frame or jamb 14. A spring 93 acts to yieldingly hold this latch in engaged position.

Pivotedly mounted upon the carriage 31 as shown at 94 is an arm 95, and one end of this arm is formed with spaced shoulders 96 and 97, the latter being relatively long. These shoulders are spaced to receive between them the bracket 89 and an arm 98 which is rigid with the latch 91 and to permit limited independent movement of the arm 89 and arm 90 with respect to the shoulders 96 and 97. The arm 95 has its lower end yieldingly forced outward by means of a spring 99, and the upper end of this arm carries a roller 100. Arranged in the path of the roller 100 is a cam arm 101 and when this roller engages this cam arm, the roller will be moved pivotally.

It will thus be seen that as the door 10 moves to a closed position, the shoulder 96 will engage the arm 89, and the door 13 will likewise be moved to a closed position. When the door 13 reaches its closed position, the latch 91 will engage the keeper 92 so that the door 13 will be locked.

When the switch 54 is closed to open the elevator door, at the beginning of opening movement, the shoulder 97 will engage the arm 98 and will move this arm against the action of the spring 93 so as to lift the latch 91 from engagement with the keeper 92. This is due to the fact that the shoulder 97 is of greater length than the shoulder 96, as contact of the roller 100 with the cam arm 101 has disengaged this shoulder 96 from the arm 89. Continued movement of the carriage will cause the arm 98 to engage the bracket 89 so that the door 13 will be opened simultaneously with the opening of the door 10.

When the doors are in closed position, the latch 91 will engage an arm 102 which forms a part of a switch 103, suitably connected in the circuit of the motor M'. The switch 103 is open when the doors are open and prevents operation of the motor M' until the doors are closed. The switch 103 represents the usual door switch for accomplishing the purpose stated, but is controlled by the latch 91.

When the elevator door is at a closed posi-

tion, the roller 100 carried by the arm 95 is in engagement with the cam arm 101 and consequently the lower portion of the arm 95 is swung inwardly and does not project outwardly from the elevator and cannot interfere with sills or other parts of the elevator shaft, thus permitting the free passage of the elevator car in the hatchway or shaft.

Having described the invention what is claimed is:—

1. An operating mechanism for an elevator door comprising a motor carried by the elevator and in open circuit with a source of electric supply, a transmission device connected with the motor, a track rail leading from the transmission device, a carriage movable upon the track rail and carrying the elevator door, means operatively connecting the transmission device with the carriage, switches located at the ends of the path of movement of the carriage and including terminals electrically connected with the motor and terminals electrically connected with a source of electric supply and circuit closers engageable with said terminals, arms carried by the carriage and adapted to engage the circuit closers and move them to open positions when the carriage arrives at the ends of its path of movement and means for reversing the flow of current to the motor.

2. An operating mechanism for an elevator door comprising a motor carried by the elevator and in open circuit with a source of electric supply, a transmission device connected with the motor, a friction clutch interposed between the motor and transmission device, a track rail leading from the transmission device, a carriage movable upon the track rail and carrying the elevator door means operatively connecting the transmission device with the carriage, switches located at the ends of the path of movement of the carriage and including terminals electrically connected with the motor and terminals electrically connected with a source of electric supply and circuit closers engageable with said terminals, and arms carried by the carriage and adapted to engage the circuit closers and move them to open positions when the carriage arrives at the ends of its path of movement.

3. An operating mechanism for an elevator door comprising a motor carried by the elevator and in open circuit with a source of electric supply, a transmission device connected with the motor, a brake for the transmission device and connected in said electric circuit, a track rail leading from the transmission device, a carriage movable upon the track rail and carrying the elevator door, means operatively connecting the transmission device with the carriage, switches located at the ends of the path of movement of the carriage and including terminals electrically connected with

the motor and terminals electrically connected with a source of electric supply and circuit closers engageable with said terminals, and arms carried by the carriage and adapted to engage the circuit closers and move them to open positions when the carriage arrives at the ends of its path of movement.

4. An operating mechanism for an elevator door and elevator shaft doors comprising a motor carried by the elevator and in open circuit with a source of electric supply, a transmission device connected with the motor, a track rail leading from the transmission device, a carriage movable upon the track rail and carrying the elevator door, means operatively connecting the transmission device with the carriage, switches located at the ends of the path of movement of the carriage and including terminals electrically connected with the motor and terminals electrically connected with a source of electric supply, and circuit closers engageable with said arms, arms carried by the carriage and adapted to engage the circuit closers and move them to open positions when the carriage arrives at the ends of its path of movement, latch members pivoted upon the shaft doors, keeper plates adapted to be engaged by said latch members, switch members pivoted adjacent said keeper plates and adapted to be engaged by the latches, terminals connected in the circuit and adapted to be closed by the switch members, an arm pivoted to the carriage and adapted to disengage the latch members from the keepers and a cam plate fixed with relation to the track rail and adapted to hold the pivoted arm away from the latch members when the elevator door is closed.

5. An operating mechanism for an elevator door comprising a motor carried by the elevator and in open circuit with a source of electric supply, a transmission device connected with the motor, a track rail leading from the transmission device, a carriage movable upon the track rail and carrying the elevator door, guide members upon which the carriage is slidably mounted, means operatively connecting the transmission device with the carriage, switches located at the ends of the path of movement of the carriage and including terminals electrically connected with the motor and terminals electrically connected with a source of electric supply and circuit closers engageable with said terminals and arms carried by the carriage and adapted to engage the circuit closers and move them to open positions when the carriage arrives at the ends of its path of movement.

In testimony whereof I affix my signature.

CHARLES W. HORTON.
